UNITED STATES PATENT OFFICE.

LABAN J. EVEREST, OF OMAHA, NEBRASKA, ASSIGNOR OF ONE-FOURTH TO
HENRY C. BETTERMAN, OF SAME PLACE.

ROTARY ENGINE.

SPECIFICATION forming part of Letters Patent No. 446,061, dated February 10, 1891.

Application filed May 17, 1890. Serial No. 352,200. (No model.)

To all whom it may concern:

Be it known that I, LABAN J. EVEREST, of Omaha, in the county of Douglas and State of Nebraska, have invented a new and Improved 5 Rotary Engine, of which the following is a full, clear, and exact description.

The object of the invention is to provide a new and improved rotary engine, which is simple and durable in construction, very effective in operation, and utilizes the motive power to the greatest advantage.

The invention consists of a fixed cylinder provided with angularly-arranged inlet-ports and a piston mounted to turn within the said cylinder and provided with recesses or buckets adapted to receive tangential pressure from the motive agent in the annular steam-inlet ports.

The invention also consists of certain parts 20 and details and combinations of the same, as will be hereinafter fully described, and then pointed out in the claims.

Reference is to be had to the accompanying drawings, forming a part of this specification, 25 in which similar letters of reference indicate corresponding parts in both the figures.

Figure 1 is a sectional side elevation of the improvement on the line xx of Fig. 2, and Fig. 2 is a transverse section of the same on 30 the line yy of Fig. 1.

The improved rotary engine A is provided with a frame B, having a suitably-constructed base C, adapted to be secured on a foundation-wall of brick or other material, placed wherever the engine is to be located. The frame B supports a cylinder D, made in the shape of a ring having an annular recess D', closed on one side by a ring-shaped head D², secured to the cylinder D by suitable bolts D³. Into 35 the recess D' of the cylinder D extends the outer edge of the piston E, made in the shape of a wheel and secured on a shaft F, mounted to turn in suitable bearings G, formed on the frame B. The wheel-shaped piston E is provided in its periphery with recesses or buckets I, against which is to act the motive agent passing through inlet-ports a, arranged angularly in the cylinder B, so as to lead the motive agent tangentially on the piston E in 40 the said buckets I. The outer ends of the ports a are connected by branch pipes J with a pipe K, closed at one end and connected at its other end with the steam-inlet pipe L. From the recess D' in the cylinder D also leads an exhaust-port b, connecting with an 55 exhaust-pipe N, leading to the outside. The exhaust-port b is arranged between two inlet-ports a, as is plainly shown in Fig. 1, while the series of inlet-ports a follow each other and are placed equal distances apart without 60 an intervening exhaust-port.

In order to prevent steam from escaping from the annular recess D' in the cylinder D, the latter is provided with packing-rings O, pressed against the face of the piston E by 65 means of suitable set-screws P, as is plainly shown in Fig. 2.

The operation is as follows: Steam entering the steam-inlet pipe L passes into the pipe K, and from the latter passes through the branch pipes J into the several inlet-ports a, discharging into the annular recess D' of the cylinder D. The steam entering the steam-space D' in a tangential line presses against the buckets or recesses I of the piston E, so 70 that the latter is rotated in the direction of the arrow a'. It will be seen that the steam entering through the port a, located near the inlet-pipe L, fills the first bucket or recess I, and is supplemented with steam from the 75 next following inlet-port a when the said recess opens into the latter port. This is repeated in all the successive ports a, so that the steam which originally passed into the bucket at the first port a, near the inlet-pipe 80 L, is not exhausted until it has passed all the inlet-ports a and opens into the exhaust-port b, located near the first inlet-port a. It will be seen that by this arrangement no motive agent whatever is wasted, and the full power 85 of the motive agent is exerted before the steam passes to the outside through the exhaust-port b. Thus it will be seen that each bucket I has a tangential pressure during nearly one entire revolution of the piston E, so that the latter is acted on with a pressure equal to as 90 many buckets as it contains multiplied by the boiler-pressure. For instance, as shown in Fig. 1, the piston E is provided with ten buckets, and if the boiler-pressure is twenty-five 95 pounds, the said piston has an average pressure of nine by twenty-five pounds, equaling 100

two hundred and twenty-five pounds, it being understood that one bucket exhausts into the port *b* while the others are under full pressure.

5 Having thus fully described my invention, I claim as new and desire to secure by Letters Patent—

1. In a rotary engine, the combination of a ring-shaped cylinder having an annular recess and provided with a series of angularly-arranged inlet-ports leading from said recess and an exhaust-port between two inlet-ports and adjacent to the first of the series of said ports, a steam-passage communicating with each inlet-port, said passage having one end closed and its other end connected with the inlet-pipe, and a wheel-shaped piston mounted to turn in the cylinder and provided on its periphery with a series of pockets corresponding in number with the number of inlet-ports, substantially as herein shown and described.

2. In a steam-engine, the combination of the ring-shaped cylinder *D*, having an annular recess *D'*, the inclined inlet-ports *a*, and

the exhaust-port *b* between two of the said inlet-ports, the pipe *K*, having one end closed and connected at the other end with the inlet-pipe, the branch pipes *J*, connecting the pipe *K* with the ports *a*, and the wheel-shaped piston *E*, provided with the buckets *I* on its periphery, substantially as herein shown and described.

3. In a rotary engine, the combination of a ring-shaped cylinder *D*, having an annular recess *D'*, the inclined ports *a*, and the exhaust-port *b*, the pipe *K*, having one end connected to the inlet-pipe, the branch pipes *J*, connecting the pipe *K* with the ports *a*, the wheel-shaped piston *E*, provided with the buckets *I* on its periphery, and the packing-rings *O*, bearing against the face of the piston, substantially as herein shown and described.

LABAN J. EVEREST.
